(57) **CLAIM**

An ornamental design for wildlife feeder legs, as shown and described.

DESCRIPTION

FIG. 1 is a front view of the wildlife feeder legs; and, FIG. 2 is a rear view of the wildlife feeder legs. The drawings include depictions of a wildlife feeder, parallelogram-shaped upper panels and the upper portion of a feeder leg which are shown in broken lines and do not form a part of the claimed design.

1 Claim, 2 Drawing Sheets
